UNITED STATES PATENT OFFICE.

GARTH G. GILPIN, OF RIVERSIDE, ILLINOIS, ASSIGNOR TO WALTER P. MURPHY, OF CHICAGO, ILLINOIS.

CORRUGATED SHEET-METAL DOOR FOR RAILWAY CARS OF THE DUMPING TYPE.

Original application filed November 14, 1919, Serial No. 337,907. Divided and this application filed July 2, 1921. Serial No. 432,260.

To all whom it may concern:

Be it known that I, GARTH G. GILPIN, a citizen of the United States, residing at Riverside, in the county of Cook and State of Illinois, have invented certain new and useful Improvements in Corrugated Sheet-Metal Doors for Railway Cars of the Dumping Type, of which the following is a specification.

10 My invention relates to the construction of railway freight cars of the type having hinged bottom sections for dumping bulk loads. It has been proposed to form these bottom sections or doors of sheet metal 15 ribbed or corrugated so as to give maximum strength and rigidity for minimum weight of metal, but the provision of the doors with corrugations as deep as desirable is attended with some difficulty. If the corrugations 20 or ribs are depressed from the sheet, having reference to the normal position of the door in the car, the depressions are likely to trap water, which is very undesirable. If the corrugations or ribs are pressed upwardly 25 from the sheet it may happen that they may project above the stationary parts of the car bottom above the cover plates for the center sill and cross bearers, for example, so that when the car is loaded with heavy articles, 30 such as rails, machinery, and the like, as sometimes is done, these articles are supported on the corrugations alone, that is, on the doors alone, instead of being carried in part by the framing or stationary portions of the 35 car bottom as is obviously preferable. The principal object of my invention is to provide a corrugated sheet metal door for cars of this type, more especially for cars known as "general service" cars (intended to serve 40 as ordinary gondola cars for the transportation of miscellaneous freight as well as bulk loads that can be dumped), the corrugations of which may project either partly or entirely below the original plane of the door 45 sheet, as circumstances may make desirable, but are so disposed as to permit water to freely drain from the depressed or downturned corrugations.

The invention consists in the novel and 50 improved arrangements and devices to be hereinafter described and claimed for carrying out the above stated object, and such other incidental objects as will appear from

the following description of certain preferred embodiments of the invention. 55

In the drawings—

Figs. 1 to 6 illustrate somewhat diagrammatically a simple form of door panel formed in accordance with my invention shown apart from the rest of the car structure; Fig. 1 being a plan view; Figs. 2 and 3 sectional views on the lines marked 2—2 and 3—3, looking in opposite directions respectively; Figs. 4 and 5 sectional views on lines 4—4 and 5—5, respectively, of Fig. 1, 65 and Fig. 6 an edge elevation taken from the low or hinged side of the door.

Fig. 7 is a plan view of a reinforced, corrugated door constructed on the same principle but modified as to the relation of the 70 crests and hollows of the corrugations with respect to the original plane of the metal sheet.

Fig. 8 is a cross sectional view on line 8—8 of Fig. 7. 75

Figs. 9 and 10 are cross sectional views taken on lines 9—9 and 10—10, respectively, of Fig. 7.

Fig. 11 is a cross sectional view through a portion of the car body and door, this figure 80 being on a smaller scale than Figs. 7 to 10.

Like characters of reference designate like parts in the several figures of the drawings.

Figs. 1 to 6 inclusive illustrate in a rather diagrammatic way a simple embodiment of 85 the invention, these figures showing the corrugated door panel apart from any of its attachments. The panel is pressed from a single sheet of metal A and is preferably formed with an integral, downturned flange 90 B. The corrugated portion of the plate is produced by pressing the plate so as to form it with a series of alternately arranged hollows C and ridges D, the crests of the latter being in the original plane of the upper surface of the plate. The hinged edge E of the plate is pressed to the level of the bottoms of corrugations C so that these corrugations or hollows can freely drain. The other side margin F and the end margins G and H are 100 left in the original plane of the plate.

Referring now to Figs. 7 to 11 inclusive, showing a modified form of door panel reinforced and hinged to a car of the "general service" type. 10 indicates the center sill of 105 the car, 11 the cross bearers, 12 the side

sheathing, 13 one of the side stakes and 14 the cover plate for the cross bearers. It will be understood that the car is constructed so as to provide a number of dumping openings on opposite sides of the center sill, these openings being normally closed by hinged bottom sections or doors which are manipulated by apparatus which forms no part of the present invention and which, therefore, 10 has been omitted from the drawings. This invention concerns the construction of a door suitable for use in a car of this type, or with other dumping cars where similar conditions prevail.

15 The door consists of a sheet metal panel 15 preferably, although not necessarily, composed of a single sheet of metal. The door sheet, as it may be termed, is formed with a central corrugated portion 16 and at one edge is hinged to the center sill 10 (the hinges being indicated at 17). The end marginal portions 18, 18 of the door sheet and the side marginal portion 19 thereof which bears against the under side of the 20 inturned part 20 of the side sheet 12 are in the same plane, that is, the original plane of the sheet before it is pressed. The corrugated portion 16 of the sheet is formed by pressing therein, in parallel arrangement, a plurality of ribs which alternately project above and below the original plane of the sheet. Those projecting upwardly preferably have their crests in a plane at the level of the cross bearer cover plates 14 and the 25 intervening center sill cover plates (not shown). The hinged margin 22 of the sheet is depressed to the level of the bottoms of the depressed corrugations. By this arrangement any moisture will drain off along 30 the depressed edge 22 of the plate instead of being trapped as would be the case if both ends of the corrugations were below the level of the adjacent uncorrugated margins. The corrugations are made to terminate within 35 the edges of the sheet so that they will give it rigidity. The configuration of the sheet as shown also adapts it to fit snugly in place under the center sill and side sheets. The center sill is shown as consisting in part of 40 T-beam 23 and in order that the door may project under the upper flange of this T-beam the extremities of the marginal portions 18 adjacent the center sill are depressed, as indicated at 24, to the level of the 45 marginal portion 22 of the sheet. To give additional strength and rigidity to the door its edges are formed with downturned flanges 25. In addition a rigidifying structure is provided for the under side of the 50 door comprising angle bars 26 running parallel with the corrugations and secured by rivets 27 to the marginal portions 18 of the door and to the flanges 25, with the interpolation of spacers 28, by rivets 29, together 55 with a Z-bar 30 secured to the members 26

and to the door sheet and extending across the ends of the corrugations and angle bars 31 near the opposite edge of the door which are riveted to the door at suitable intervals.

This application is a division of my co-pending application Serial No. 337,907, filed 70 November 14, 1919.

I claim:

1. In combination with a railway car having a dumping opening in the bottom, a sheet metal door to close the same formed with strengthening corrugations which terminate within the edges of the door sheet, said door sheet being formed so that portions of the corrugations project below the plane 75 of adjacent uncorrugated parts of the sheet while the corrugations at one end are entirely above the uncorrugated marginal part of the sheet adjacent thereto for drainage purposes.

2. In combination with a railway car having a door opening in the bottom, a sheet metal door to close the same formed with a plurality of corrugations extending across the door sheet between opposite edges, the portions of the corrugations adjacent one of said edges projecting below the adjacent marginal parts of the sheet while the opposite ends of the corrugations stand substantially above the uncorrugated part of the 95 marginal sheet adjacent thereto.

3. In combination with a railway car having a door opening in the bottom, a sheet metal door to close the same formed with a plurality of parallel corrugations extending 100 across the door sheet between opposite edges at right angles to said edges, the portions of the corrugations adjacent one of said edges projecting below the adjacent marginal parts of the sheet while the opposite ends 105 of the corrugations stand substantially above the uncorrugated part of the marginal sheet adjacent thereto.

4. In combination with a railway car having a dumping opening in the bottom, a sheet metal door to close the same formed with a depressed portion which extends to one edge of the door sheet, said depressed portion having pressed therein corrugations 110 upstanding therefrom which terminate within the edges of the sheet.

5. In combination with a railway car having a dumping opening in the bottom, a sheet metal door to close the same formed with a depressed portion which extends to one edge of the door sheet, said depressed portion having pressed therein corrugations 115 upstanding therefrom which extend toward but terminate short of said edge.

6. In combination with a railway car having a dumping opening in the bottom, a sheet metal door to close the same formed with a depressed portion which extends to one edge of the door sheet, said depressed portion having pressed therein a plurality 125

of upstanding, parallel corrugations at substantially right angles to said edge which merge into the door sheet at opposite ends.

7. In combination with a railway car having a dumping opening in the bottom, a sheet metal door to close the same formed with a depressed portion which extends along one edge of the door sheet, said door being formed with corrugations which project above the depressed portion of the door sheet but below the top of the other marginal portions thereof.

8. In combination with a railway car having a dumping opening in the bottom, a sheet metal door to close the same formed with a depressed portion which extends along one edge of the door sheet leaving marginal portions along the other three edges which are in a higher plane, said sheet being formed with corrugations projecting entirely above the depressed margins thereof slightly above the plane of said other marginal portions.

9. In combination with a railway car having a dumping opening in the bottom, a sheet metal door to close the same formed with a depressed portion which extends along one edge of the door sheet leaving marginal portions along the other three edges which are in a higher plane, said sheet being formed with a plurality of parallel corrugations at substantially right angles to the depressed margin of the sheet and projecting above the same.

35 10. In combination with a railway car having a dumping opening in the bottom, a sheet metal door to close the same formed with a depressed portion which extends along one edge of the door sheet, said sheet being formed with a plurality of parallel corrugations at substantially right angles to the depressed margin of the sheet and projecting above the same, the sheet being formed with depending flanges to further 45 stiffen the same.

11. In combination with a railway car having a dumping opening in the bottom, a sheet metal door to close the same formed with a depressed portion which extends along one edge of the door sheet, said sheet being formed with a plurality of parallel corrugations at substantially right angles to the depressed edge of the sheet and projecting above the same, and reinforcing 55 members on the under side of said door which cross the ends of the corrugations.

12. In combination with a railway car having a dumping opening in the bottom, a sheet metal door to close the same formed with a depressed portion which extends along one edge of the door sheet, said sheet being formed with a plurality of parallel corrugations at substantially right angles to the depressed edge of the sheet and projecting upwardly therefrom, and a rein-

forcing structure on the under side of the car comprising members along the edges of the door parallel to the corrugations.

13. In combination with a railway car having a dumping opening in the bottom, a sheet metal door to close the same formed with a depressed portion which extends along one edge of the door sheet, said sheet being formed with a plurality of parallel corrugations at substantially right angles to the depressed edge of the sheet and projecting upwardly therefrom, a reinforcing structure on the under side of the car comprising members along the edges of the door parallel to the corrugations, and members 80 extending at right angles to the corrugations.

14. In a railway car of the type described, the combination of the fixed portion of the car bottom constructed to provide a dumping opening, and a hinged door to close said opening formed of sheet metal having pressed therein corrugations, the crests of which are substantially flush with the upper surface of the fixed portion of the car bottom.

15. In a railway car of the type described, the combination of the fixed portion of the car bottom constructed to provide a dumping opening, and a hinged door to close said opening formed of sheet metal having pressed therein corrugations, the crests of which are substantially flush with the upper surface of the fixed portion of the car bottom, said corrugations projecting below the 100 marginal portions of the door sheet on three sides of the door and above the marginal portion of the door sheet on the other side thereof.

16. In a railway car of the general service type, the combination of the center sill and cross bearer of the car and their cover plates, and a door hinged to said center sill below the top of the same consisting of a sheet metal panel having a depressed portion 110 which extends along the edge thereof adjacent the center sill and formed with corrugations upstanding therefrom to substantially the level of the upper surface of said cover plates.

17. In combination with a railway car having a dumping opening in the bottom, a sheet metal door for closing said opening formed with corrugations which are depressed with respect to a flat marginal portion of the door, and a reinforcing member on the under side of the door crossing the corrugations, fastened at opposite ends to said flat marginal portion, and bent to extend under said corrugations.

18. In combination with a railway car having a dumping opening, a sheet metal door to close the same formed with corrugations, the crests of which are substantially flush with the car flooring when the door

is closed and the hollows of which merge into the surface of the sheet, for the purpose described.

19. In combination with a railway car having a dumping opening, a sheet metal door to close the same formed with stiffening corrugations, and with marginal portions adapted to rigidify the margins of the sheet; said corrugations and marginal portions being so proportioned with relation to each other that the crests of the corrugations are substantially flush with the flooring of the car when the door is closed.

20. A door structure for railway cars of the dumping type comprising a sheet metal panel formed with angular rigidifying marginal portions and with rigidifying ribs formed on said panel adapted to be supported substantially flush with the flooring of the car when the door is closed.

21. A door structure for railway cars of the dumping type comprising a sheet metal panel formed with corrugations which project below the plane of certain adjacent uncorrugated parts of the sheet while the deepest parts of said corrugations are flush with an uncorrugated part of said sheet.

22. A door structure for railway cars of

the dumping type comprising a sheet metal panel formed with a depressed portion which extends along one edge of the door leaving marginal portions along the other three edges which are in a higher plane, said panel being formed with a plurality of parallel corrugations which project entirely above the said depressed margin of said panel.

23. A door structure for railway cars of the dumping type, comprising a sheet metal panel provided with rigidifying marginal portions and with a plurality of corrugations extending across said panel, the corrugations at the center of the panel being of greater length than the corrugations at the sides thereof.

24. A door structure for railway cars of the dumping type, comprising a sheet metal panel provided with marginal portions which extend along three edges of the panel at a higher plane than the marginal portions extending along the other edge of said panel, and formed with corrugations of substantially equal length which project entirely above the lower marginal portion of the panel.

GARTH G. GILPIN.
